UNITED STATES PATENT OFFICE.

HORACE A. CARTER, OF NEEDHAM HEIGHTS, MASSACHUSETTS.

UNDERGARMENT.

1,244,174.

Specification of Letters Patent. Patented Oct. 23, 1917.

Application filed December 16, 1916. Serial No. 137,436.

To all whom it may concern:

Be it known that I, HORACE A. CARTER, a citizen of the United States, and a resident of Needham Heights, in the county of 5 Norfolk and State of Massachusetts, have invented an Improvement in Undergarments, of which the following description, in connection with the accompanying drawings, is a specification, like characters on the drawings representing like parts.

This invention relates to undergarments, and particularly to union undergarments.

In order that the principle of the invention may be readily understood, I have disclosed a single embodiment thereof in the accompanying drawings, wherein—

Figure 1 is a front elevation of a union undergarment embodying my invention;

Fig. 2 is a rear elevation thereof;

Fig. 3 is a view similar to Fig. 1, but representing the front upper portion of the garment as open;

Fig. 4 represents certain gussets preferably employed in the undergarment to which 20 my invention peculiarly but not necessarily applies; and

Fig. 5 is a detail showing said gussets as applied to the garment.

In accordance with my invention, I provide an undergarment with one and preferably with two overlapping extensions at the front, having numerous advantages herein-after more fully set forth. This construction is peculiarly applicable to union undergarments in that each size of garment can be readily fitted to a person to whom the nether part of the garment fits regardless of the bust measurement of the person. It is of frequent occurrence that a union undergarment, the nether portion of which will fit, will not fit the bust measurement. This requires, therefore, the making of union undergarments of different bust measurements for the same nether measurement, and vice 45 versa.

While in its preferred embodiment my invention is peculiarly adapted therefore to union undergarments, it is not restricted thereto.

Referring more particularly to the drawings, I have in Figs. 1, 2 and 3 indicated a union undergarment having a body 1, arms 2—2 and legs 3—3, all preferably integral. The garment may be of knitted or woven 55 material, but preferably is knitted and preferably the wales run in a vertical direction

through the said parts. The garment may be of the drop seat or closed crotch type, or of any other suitable type for men or women. I have herein represented it as of 60 the closed type, and preferably for that purpose I provide two gusset portions respectively indicated at 4, 5 in Figs. 4 and 5, the gusset 4 being herein designated as the left-hand gusset, because in practice the greater 65 portion of its perimeter is seamed to the left-hand end of the garment, and the gusset 5 being termed the right-hand gusset since the greater portion of its perimeter is seamed to the right-hand leg of the garment. If the 70 garment be a knitted one, the knitted wales extend longitudinally of the gussets 4, 5. The lateral edges 6, 7, 8 and 9 of gussets 4, 5 are preferably cut upon curved lines which converge toward each other. Each gusset is 75 shown as having a square upper end 10, 11, which in the garment are lapped past each other and secured to the body of the garment at the rear, as indicated in Fig. 2. The edge 7 of the gusset 4 and the edge 8 of the 80 gusset 5 constitute the free edges of the garment at the rear. The edge 6 of the gusset 4 and the edge 9 of the gusset 5 which, as previously described, are preferably cut upon curved lines are seamed to the straight edges 85 of the body portion of the garment, thus giving increased width across the hips and thighs of the wearer.

I preferably provide the gussets 4, 5 with gores numbered respectively 12, 13, 14 and 90 15. The gore 12 of the left-hand gusset 4 constitutes a thigh widening gore and is attached along both its legs to the inside seam of the left leg, thus enlarging the diameter 95 of the upper portion of that leg, and the gore 13 of said left gusset constitutes in effect a suspensory-forming gore. The said gore 13 is carried over and attached to the inside seam of the leg just below or at the crotch, 100 as indicated in Figs. 1 and 3.

The gore 15 of the right gusset 5 is seamed along both its edges to the inside seam of the right leg, thus enlarging the diameter of the upper portion of the leg, and the gore 14 constitutes a suspensory-forming gore which 105 is carried across and seamed to the inside seam of the left leg at the upper portion thereof just below or at the crotch.

The gores 13, 14 are, in the completed garment, superimposed one upon the other. Viewing Figs. 1 and 3, it will be observed 110 that both of the suspensory-forming gores

13, 14 are positioned wholly at one and the same side of the axial line of the crotch, which may be defined as the median line of the garment. The upper ends of the said 5 gores 13, 14 are superimposed as described and are secured to the upper edges of the legs wholly at one side of the said axial crotch line.

In accordance with my invention I provide the garment at the front thereof with 10 preferably two flaps or extensions herein indicated at 16, 17. These flaps or extensions are of such length as to afford protection to the lungs and throat of the user, but are not 15 of sufficient length to cover the abdomen. Thus a double thickness over the abdomen is prevented, while thorough protection of the bronchial tubes and of the lungs is afforded. The said flaps 16, 17 terminate at substan-

20 tially the point indicated, and from there to the crotch or throughout the remainder of the garment is preferably closed, except as some usual toilet opening may be provided at or substantially at the crotch portion.

25 These flaps are preferably triangular in shape, substantially as shown, and are tapered downward to more or less sharp lower ends. While the said flaps or extensions may be knitted integrally with the body of the 30 garment, they are preferably sewed or otherwise secured thereto, as indicated by the lines 18, 19. This permits the said flaps or extensions to be formed of material differing from that of the body of the garment. For 35 example, the body of the garment may be made wholly or partially of cotton, and the flaps and extensions may be made of wool or silk in such a manner as to afford additional protection.

40 The flaps or extensions 16, 17 serve several important purposes. It is of frequent occurrence that a union undergarment which otherwise fits is either too snug or too loose at the chest portion. By providing an overlapping flap or preferably overlapping flaps, and particularly by providing adjusting means for securing these flaps, I have provided means whereby a union undergarment will fit at all parts thereof. Any suitable 45 securing means may be provided for the flaps, but preferably I provide the left-hand side of the garment with a button 20, which may be positioned in any one of a plurality of button holes 21 in the corresponding flap 50 or extension 17. The outside of the flap or extension 16 is, in this embodiment of the invention, provided with a button 22, which may be positioned in any one of a plurality of button holes 23 in the body of the garment 55 at the right of the flap or extension 17. By providing a series of button holes or other adjustable connections, the garment may obviously be fitted to persons of differing chest or neck measurement. It not 60 infrequently happens that the neck measure-

ments of persons vary while the other measurements may be correspondingly the same. Furthermore, the wearer at some times desires to have the garment close fitting at the neck and at other times loosely fitting, 70 as, for example, in weather of different temperatures. This is particularly the case where the same weight of garment is worn throughout the year. Preferably the flaps or extensions 16, 17 as well as the remainder 75 of the neck portion are provided with a non-expansile border, this being preferably secured by a bias, woven or bias-cut woven cloth elastically seamed to the garment as disclosed in my Patent No. 1,145,402. 80

Preferably at the lower portions, the flaps or extensions 16, 17 are transversely seamed and secured to the body portion of the garment.

Inasmuch as the garment is preferably 85 provided with two flaps 16, 17, it is evident that the double thickness provides ample chest and throat protection, and this is particularly true if said flaps or extension be 90 of such material as wool irrespective of the material of the body of the fabric.

Even though the garment be a knitted one, it is not essential that the flaps 16, 17 be knitted, as within the scope of my invention they may be of woven or other material. Preferably, however, they are of the same formation as the body of the garment. 95

The front opening of the garment extends from the neck opening vertically down the center of the chest, and a substantially triangular flap is secured along each edge of said front opening, said flaps each lapping past the other and terminating at their upper ends substantially below the top of the shoulders, the buttons or other means securing the said flaps at their upper outer corners to the body of the garment between the neck opening and the arm holes and relatively remote from each and also laterally beyond the neck opening. Said flaps 100 are preferably right-triangular in shape, the hypotenuse of each extending downward and inward. Owing to the fact that the opening is positioned as described it is possible to use small pieces for the flaps which 105 can be taken from the by-product, and otherwise would be sold as scrap or waste.

An undergarment constructed in accordance with my invention has numerous advantages. Not only does it afford ample 110 protection of the bronchial tubes and of the lungs, but a double thickness of garment over the lower portion of the body is avoided, this being objectionable. Furthermore, the garment is very readily secured by but 115 two buttons for which may be substituted stays, hooks or other suitable fastening means, and the garment is one which may be put on and taken off with the greatest 120 ease. 125

It will be evident from the foregoing description that my invention is peculiarly adapted for use in a union undergarment, though it is not restricted thereto.

Having thus described one illustrative embodiment of my invention, I desire it to be understood that although specific terms are employed, they are used in a generic and descriptive sense and not for purposes of limitation, the scope of the invention being set forth in the following claims.

Claims:

1. An undergarment having a front opening extending from the neck opening vertically down the center of the chest, and terminating at a point substantially at the lower end of the chest, a substantially triangular chest flap secured along each edge of said front opening, said flaps eachlapping past the other and terminating at their upper ends substantially below the top of the shoulders, and means to secure said flaps at their upper, outer corners to the body of the garment between the neck opening and the arm holes and relatively remote from each.

2. An undergarment having a front opening extending from the neck opening vertically down the center of the chest, a sub-

stantially triangular flap secured along each edge of said front opening, said flaps lapping past each other substantially to cover the chest, and terminating at their upper ends substantially below the tops of the shoulders, and adjustable means to secure each of said flaps at its upper outer corner to the body of the garment between the neck-band and the nearest arm hole and relatively remote from each, and laterally beyond the neck opening.

3. An undergarment having a front opening extending from the neck opening vertically down the center of the chest, a substantially right-triangular chest flap secured along each edge of said front opening with the hypotenuse extending downward and inward, said flaps each lapping past each other and having their upper outer corners terminating between the neck-band and the arm holes and relatively remote from both, and means to secure each of said upper outer corners to the body of the garment laterally beyond and relatively remote from the neck of the wearer.

In testimony whereof, I have signed my name to this specification.

HORACE A. CARTER.
